(57) **CLAIM**

The ornamental design for a starry projector lamp, as shown and described.

DESCRIPTION

FIG. 1 is a first perspective view of a starry projector lamp showing our new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

The broken lines shown in the drawings depict portions of the starry projector lamp in which the design is embodied that form no part of the claimed design.
